SUCTION NOZZLE

Eric Edström, Stockholm, Sweden, assignor to
 Electrolux Corporation, Dover, Del., a corpora-
 tion of Delaware

Application June 26, 1936, Serial No. 87,399
 In Switzerland July 2, 1935

3 Claims. (Cl. 15—155)

My invention relates to suction nozzles for use in connection with a vacuum cleaner and particularly to duplex nozzles provided with openings of different sizes which may be selectively connected to the source of suction. When the larger opening is in use it will cover a larger surface, thereby increasing the speed of cleaning. However, if a concentrated suction is desired in order to remove dirt which the larger opening 5 will not pick up, the small opening may be brought into use.

The objects and advantages of my invention will be apparent from the following description considered in connection with the accompanying 15 drawing which forms part of this specification, and of which:—

Fig. 1 is a cross-sectional view of a preferred embodiment of my invention; and

Fig. 2 is a front view of a portion of a nozzle shown in Fig. 1.

Referring to the drawing, reference character 10 designates a hollow elongated nozzle body formed with an elongated suction opening 11. Body 10 is rigidly connected to a nipple 12 which 25 may receive a conduit connected to a source of suction. Nipple 12 communicates with the interior of body 10 through an opening 13. Pivoted within the body at either side of the opening are partitions or valve plates 14. The interior of the forward and rear walls of the nozzle body are flat and valve plates 14 are dimensioned so as to fit between these walls. The pivots 15 to which the valve plates are rigidly secured are rotatably mounted in the forward wall of the nozzle body and project therethrough. The outer ends of pivots 15 have rigidly affixed thereto intermeshing gear segments 16, while one of the pivots is provided with knurled knob 17.

In the position of the parts shown in full lines 40 in Fig. 1, valve plates 14 cut off communication between the ends of the elongated opening 11 and the opening 13. Consequently, all of the air is constrained to flow through the small central portion of opening 11 between the valve plates 14. This results in a strong suction at this point. If a more distributed suction is desired, knob 17 is rotated in a counter-clock-wise direction. By virtue of the gear segments 16 the valve plates are rotated in opposite directions to 50 the positions shown in dash and dot lines in Fig. 1. In this position they do not interfere with the flow of air through the nozzle opening

11 and consequently air is drawn in through the entire extent of the opening.

In order to retain the valve plates 14 in either of the positions in which they are set, a spring 18 is secured at 19 to the nozzle body and at 20 5 to one of the gear segments 16. In the position shown the spring passes to one side of the pivot point 15 and will tend to rotate the gear segment to which it is connected in a counter-clock-wise direction. When the segment is rotated by hand 10 to its other extreme position, the spring passes to the other side of the pivot point and consequently will tend to rotate the segment to which it is connected in a clock-wise direction. Hence, the spring tends to retain the segments in either 15 position in which they are put.

While I have shown and described one more or less specific embodiment of my invention it is to be understood that this has been done for purposes of illustration only, and that the scope 20 of the invention is not to be limited thereby, but is to be determined by the appended claims viewed in the light of the prior art.

What I claim is:—

1. In a suction nozzle, a hollow elongated body 25 formed with an elongated suction opening, said body being formed with an outlet communicating with the central part thereof and adapted to be connected to a source of suction, and a partition pivotally mounted in said body to one side 30 of said outlet, and means for pivoting said partition between a position within said body blocking the path of flow from one end of said hollow elongated body to said outlet and a position also within said body but removed from said path 35 of flow.

2. In a suction nozzle, a hollow body having a centrally located outlet adapted to be connected to a source of suction and having elongated branches on either side of said outlet and forming an elongated suction opening, pivotally mounted members disposed within said hollow body on either side of said outlet, and means for pivoting said members between a position within said body in the path of flow from said branches to said outlet and a position also within said body but removed from said path.

3. A suction nozzle as claimed in claim 2 including means for simultaneously pivoting both of said members.

ERIC EDSTRÖM.
